William Clark Whitehurst Esq.

Scitton Patent

The Schedule, referred to in these ~~scitton~~ Patent and working part of,
the drawing containing a description. In the words of, the late William
Clark himself, of his improvements to a Machine or device for the
purpose of propelling Canal & other boats Rags and Water Crops

To all whom these presents shall come.

Whereas I, William Clark of Whitehurst in the County of
Montgomery and State of Newyork, have invented a new and
useful machine or device for the purpose of propelling, Canal and other
Boats Rags and Water Crops; and that the following is a full and
exact description of the construction and operation of said machine
as invented by me.

The machine is on the principle of a screw the screw
is threaded so it may be forced to revolve around a small shaft one
two, three or more times as will best suit the motion of the machine
as you please. The size of the screw to be regulated by the size of the
shaft attached to the screw is to be composed of, Wood, Iron, Copper, Brass
Iron, or any other species of metal best adapted to the construction of the
screw. There is to be a small cog wheel fitted on the
shaft as will best suit the gearing to the boat.

This machine is intended to be applied to either end or both
ends, or both sides or in the middle, of the boat intended to be propelled
at the option of the Patentee or the person or persons having a legal right
to use the same.

This machine or screw is intended to be used to propel
Canal Boats having Boats and every other species of boat, Rags and
Water Crops. It is intended to be put in motion by steam power horse power
or hand power, or any other power. This machine or screw has an advantage
